UNITED STATES PATENT OFFICE

FRANK MAGIDSON, OF PITTSBURGH, PENNSYLVANIA, ASSIGNOR TO PITTSBURGH TAG COMPANY, A CORPORATION OF PENNSYLVANIA

SAFETY TICKET

Application filed January 13, 1932. Serial No. 586,267.

This invention relates to a marking device, and in particular to a marking device having a ticket portion and a safety fastener attached thereto for readily applying the ticket to an article or garment.

At the present time there are many types of tags on the market commonly called pin tickets by the Patent Office, in which a fastener is provided for readily securing the ticket to an article to be marked. None of these tags or pin tickets known to me, however, are satisfactory for use in certain industries, such as cleaning establishments and the like where it is necessary to mark for identification fragile garments and the like, because the fasteners are of such construction that there is danger of tearing or injuring the garment during the cleaning process, or the fasteners cannot be removed without leaving holes or otherwise injuring the garments to which they were applied.

Another objectionable feature of these pin tickets is that the ticket portions, which are usually made of cloth, have a tendency to curl when they are wet or immersed in a cleaning fluid, making it difficult to read the identification marking thereon without first straightening out the ticket.

One object of this invention is to provide a safety identification ticket which may be readily applied to an article and which will not injure or tear the most fragile article during the application or removal thereof.

Another object of this invention is to provide a safety ticket which has no projecting or uncovered metallic ends to catch on the article.

A further object is to provide a safety ticket for marking articles which will remain substantially flat under all conditions and permit the markings on the ticket to be readily examined.

These and other objects which will be made readily apparent to those skilled in this particular art are accomplished by means of this invention, one embodiment of which is illustrated in the accompanying drawing, wherein:

Figure 1 is a view in perspective of a safety ticket embodying my invention;

Fig. 2 is an enlarged view of a staple embodying a modification of my invention, and

Fig. 3 is a diagrammatic view in perspective illustrating a method for making my improved safety ticket.

55

Broadly, my improved safety ticket comprises a fastener of safety pin construction having a pointed leg 11 and a stationary leg 12 to which a tag or ticket 13 is secured. The ticket portion is stiffened thereby and prevented from curling to any great extent under any conditions.

Referring to the drawing in detail, 10 designates a fastener of safety pin construction having a pointed leg 11 and a stationary leg 12 to which a tag or ticket 13 is secured. The tag or ticket 13, which may be formed of any suitable material, such as cloth, has one end thereof folded back upon itself, as at 14, so as to form a loop around the stationary leg 12 of the fastener. The folded end 14 is fastened to the body of the ticket 13 to secure the tag to the leg 12 of the fastener 10 by a wire stapling member 15 which extends transversely of the ticket and is spaced from and is 75 parallel to the stationary leg 12. By spacing the stapling member 15 a substantial distance from the stationary leg 12 of the pin, the stapling member tends to reinforce and stiffen the tag so that it is prevented from 80 curling around its longitudinal axis when it becomes wet or is immersed in a fluid.

While I have shown a wire stapling member securing the folded end 14 to the body of the tag 13 it is understood that other means, 85 such as sewing, stitching, or the like, may be employed to secure the tag to the fastener without departing from my invention.

In Figure 2, I have shown a modified form of wire stapling member 16 in which the 90 ends of the wire are bent inwardly as at 17 so that they project into the ticket itself whereby the ends of the staple are completely covered. A stapling member of this construction makes it possible to use the ticket 95 on the finest quality of garments during a cleaning or other process without any danger of the ends of the stapling member catching on another article during the cleaning process and tearing the same.

100

In making my improved tag (Fig. 3), the fastener 10 is fed from any suitable source (not shown) in such a way it is positioned over the end of a roll of tag forming material 18 fed from a reel 19 with the stationary leg 12 facing toward the roll. The end of the tag forming material extends slightly beyond the pointed leg 11 of the fastener. While the fastener is held in this position 10 a finger 20 forces the end of the material upwardly between the legs 11 and 12 of the pin and folds it back upon itself so that it is looped around the stationary leg 12.

The finger 20 is provided with a projection 15 21 on the end thereof which engages the stationary leg 12 and holds the end of the material against the body thereof. While the finger is still engaging the stationary leg of the pin, the wire staple 15 is struck by a 20 stapler 22 which forces the staple through the material and bends the ends on the opposite side thereof toward each other securely fastening the end of the material around the leg 12. As soon as the stapling operation 25 has been completed the finger 20 is moved to its inoperative position, the fastener 10 is grabbed by suitable mechanism (not shown) and is pulled away from the fastener holding mechanism, pulling with it a length 30 of the tag forming strip from the reel 19. When a length of material sufficient to form the desired tag has been pulled from the reel a cutter or knife indicated at 23, is operated which severs the strip and permits the completed safety ticket to fall into a receptacle 35 or other hopper (not shown).

It is readily apparent from the foregoing description that I have provided a safety ticket which may be easily applied to and 40 removed from a garment, which will not injure the article to which it may be attached, has no exposed metallic points to catch on and tear the article, and the markings or identifications thereon will be readily discernible 45 since it will not curl to any marked degree under any set of circumstances.

It is understood that certain changes, modifications, or substitutions may be made herein without departing from the spirit of my invention or the scope of the appended claims.

What I claim as new and desire to secure by Letters Patent is:

1. A fastener of safety pin construction having a strip of tag forming material looped 55 around the stationary leg thereof and a member for securing said strip to said pin, said member having the ends thereof embedded in the strip.

2. A tag comprising a fastener of safety pin construction, a strip of tag forming material having the end looped over one leg of said fastener and a staple extending transversely of said strip for securing it to said pin, the ends of said staple being bent inwardly and 60 extending into said material.

3. A pin ticket comprising a safety fastener member having a stationary leg, a ticket member having one end folded upon itself to form a loop for receiving the stationary leg of said fastener, and a staple member having its ends passed through the folded end and body of said ticket and bent over said ticket to secure the ticket to the fastener, said staple member being parallel to and spaced from said stationary leg to reinforce said ticket member and to prevent the same from curling. 70 75

4. A pin ticket comprising a safety fastener member having a stationary leg, a cloth ticket member having one end folded upon itself to form a loop for receiving the stationary leg of the fastener, and a staple member having its ends passed through the folded end and body of said ticket and bent over and imbedded in said ticket to secure it to the leg of 80 said fastener, said staple member being parallel to and spaced from said stationary leg to reinforce the ticket and to prevent it from curling around its longitudinal axis. 85

5. A pin ticket comprising a safety fastener having a stationary leg, a ticket member having one end folded upon itself to form a loop for receiving the stationary leg of the fastener and a staple member having its ends passed through the folded end and body of 90 said ticket and bent over said ticket to secure it to the fastener, said staple member being parallel to and spaced from the stationary leg and extending substantially the full width of said ticket to reinforce said ticket member 95 100 and to prevent the same from curling.

In testimony whereof, I have hereunto subscribed my name this 12th day of January, 1932.

FRANK MAGIDSON.
